FLOOR MOP HANDLE

Filed June 4, 1929

INVENTOR,
Ole J. Hoiem.
BY David E. Bain,
ATTORNEY.

UNITED STATES PATENT OFFICE

OLE J. HOIEN, OF BELLINGHAM, WASHINGTON

FLOOR-MOP HANDLE

Application filed June 4, 1929. Serial No. 368,385.

My invention relates to improvements in floor mop handles, and has for an object to provide a device of this kind which supplies within itself means to retain the mop by hand when being rinsed, wrung out, or moved over the floor.

Another object of my improvement is to provide a mop handle having a hand hold and a wringing handle relatively disposed for convenient grasping in one hand when used in mopping. Another object of my improvement is to provide a mop handle adapted to engage the rim of a bucket to retain the mop above the dirt in the bottom of the bucket while the mop is being wrung out in the rinsing water therein.

Other objects of my improvement will appear as the description proceeds.

I attain these and other objects of my improvement with the mechanism illustrated in the accompanying sheet of drawings, forming a part of this specification, in which Figure 1 is a side elevation of my mop handle with mop attached in operative position in a bucket with the rim of which it is engaged while the mop is being wrung out by the hands of an operative, not shown, Fig. 2 is a side elevation of my mop handle with mop attached while being moved over a floor in washing or wiping operation with the wringing mechanism and hand hold in position for being grasped by one hand of the operative, not shown, and Fig. 3 is a plan view of the mop handle shank and eye when segregated.

Similar characters designate similar parts in the several views. Certain parts are broken away for lack of space for the full relative dimensions thereof.

With more particular reference to the designated parts: A hollow straight handle 4 has ferrule 5 fastened to its upper end to which is rigidly attached hand hold 6 which is preferably of rectangular shape with upper side 7 and lower side 8 substantially straight and each adapted for being grasped separately by one hand.

Ferrule 9 is fastened to the lower end of the handle and has handle shank 10 rigidly attached thereto preferably on the same side 50 of the handle as in hand hold 6. Shank 10

terminates in transversely long eye 11. The main body of the shank is offset from the handle by the shape thereof and has notch 13 shaped therein to engage with the rim of a bucket. Notch 13 may be provided by a lug 55 welded to the shank but I prefer to shape the shank to provide it as shown. Near eye 11 the shank bends toward the handle axis at 12 to cause the plane of said eye to be inclined to said axis and to bring said eye in approximate nearness to said axis. The material of which the shank is made and the size thereof provide strength to maintain eye 11 in approximately its illustrated position relative to the other parts of the handle. 65

Mop rod 14 is preferably a straight shaft mounted for revolution and reciprocation in hollow handle 4, its upper end is bent to form crank 15 and handle 16 while its lower end is shaped to form long eye 17 transverse to the shaft the plane of which is preferably at right angles with the plane of crank and handle 15, 16. 70

Mop cloth 18 is fastened in the usual way in eyes 11 and 17. Bucket 19 may be any 75 suitable water receptacle without fixtures or appurtenances, my mop appliance being self contained and in itself complete.

In operation: In Fig. 1 the mop assembly is shown in the preferred wringing position. 80 Part 8 of the hand hold is grasped by one hand of the operator while crank handle 16 is held in the other hand. Shank notch 13 is engaged with the rim of bucket 19 in which the mop is thus suspended. Crank handle 16 is drawn outward placing the mop under tension between eyes 11 and 17 when crank 15 is turned revolving eye 17 and thereby twisting the upper end of the mop while the lower end thereof is held in eye 11. The 85 length of crank 15, the good holds provided by crank handle 16 and hand hold 8 for the hands of the operative unite to afford easy mop-wringing means and this part of the operation may be effectively done with ease.

To rinse the mop notch 13 is disengaged from the bucket and the mop lowered into the water therein when, after untwisting the mop by the reverse revolution of the crank, the 90 mop rod 14 is reciprocated in handle 4 by 100

hold on crank 15 thus sousing it back and forth to bring the water into contact with all parts thereof.

If the floor is being washed, after rinsing the mop and while wet it is removed from the bucket and placed on the floor with shank 10 and hand hold 6 vertically upward. Crank 15 is placed alongside of side 7 of the hand hold, both are grasped in one hand and while thus held the mop is drawn thereby back and forth over the floor till it is again desired to rinse it. This and the wringing of the mop are accomplished as above described. To dry the floor with the mop it is placed thereon after having been wrung out as above described. In this manner the work may proceed effectively and easily till finished.

Having thus disclosed my invention, what I claim as new therein and desire to secure by Letters Patent is,—

1. A mop handle consisting of a hollow staff, a mop rod mounted for revolution and reciprocation in said staff projected from both ends thereof, a crank fastened on the upper end of said mop rod, an eye fastened on the lower end of said mop rod, a shank fastened on the lower end of said staff offset therefrom, an eye fastened on the lower end of said shank disposed to cooperate with said rod eye to hold a mop cloth, and a hand hold fastened on the upper end of said staff having two spaced frame members normal to said staff one of which is adjacent said upper end of the staff.

2. A mop handle consisting of a hollow staff, a mop rod mounted for revolution and reciprocation in said staff projected from both ends thereof, a crank fastened on the upper end of said mop rod, a mop eye fastened on the lower end of said mop rod, a shank fastened on the lower end of said staff offset therefrom having a notch therein engageable with the edge of a bucket, a mop eye fastened on the lower end of said shank disposed to cooperate with said eye on the mop rod to hold a mop cloth, and a hand hold on the upper end of said staff having a member projecting at right angles from said staff adjacent said upper end thereof.

OLE J. HOIEN.
